(57) **CLAIM**

The ornamental design for a guard for trunk and large limb transport, as shown and described.

DESCRIPTION

FIG. 1 is a front, left-side, top perspective view of a guard for trunk and large limb transport, showing the new design; FIG. 2 is a front elevational view thereof; FIG. 3 is a rear elevational view thereof; FIG. 4 is a left-side elevational view thereof; FIG. 5 is a right-side elevational view thereof; FIG. 6 is a top plan view thereof; and, FIG. 7 is a bottom plan view thereof.

The evenly spaced dashed lines depict parts of the guard for trunk and large limb transport that form no part of the claimed design. The long-short-long dashed break lines bound by brackets indicate that an indeterminate length of the guard for trunk and large limb transport may exist between the break lines. The break lines and the appearance of any portion of the guard for trunk and large limb transport between the break lines form no part of the claimed design.

1 Claim, 4 Drawing Sheets
